Robert Smilges, Buffalo, N.Y., assignor to American Brake Shoe Company, New York, N.Y., a corporation of Delaware

Original application Jan. 16, 1956, Ser. No. 559,438, now Patent No. 2,927,558, dated Mar. 8, 1960. Divided and this application Apr. 15, 1957, Ser. No. 652,925

7 Claims. (Cl. 137—108)

This invention relates to hydraulic apparatuses and it may be applied with facility and advantages to hydraulic apparatuses in the nature of presses.

An object of the invention is to provide improved hydraulic apparatus of the type hereinafter described.

Another object of the invention is to provide improved structure which when applied to a hydraulic press, for example, imparts improved modes of operation thereto.

Another object of the invention is to provide improved and simplified apparatus for use, for example, in a hydraulic press which will cause the ram thereof to have high traverse speeds with maximum of expended pressing energy and in which a low horsepower motor may be employed as the prime mover.

Another object of the invention is to provide improved apparatus which imparts an improved mode of operation to the ram of a hydraulic press, for example, and which is fully automatic in controlling the operation of the press ram during each stroke or cycle of the latter once the stroke or cycle is initiated.

Another object of the invention is to provide improved apparatus in a hydraulic press, for example, wherein by the press ram is caused to descend at a rapid rate until it engages work on the press bed and then to descend at a slower or working rate while increasing its working pressure to a predetermined limit and when such pressure is reached to reverse its direction of travel and travel at a high rate of speed to its starting position.

Another object of the invention is to provide improved apparatus as set forth in the foregoing object wherein the press ram may be caused to dwell against the work after said predetermined ram pressure has been reached and in which, after said dwell period is completed the ram returns to its starting position at a high rate of speed.

Another object of the invention is to provide an improved hydraulic apparatus for operating the ram of a press, for example, wherein the ram is operated by two separate volumes of hydraulic liquid derived from two sources and which volumes of liquid are first merged and directed to the ram motor to cause the ram to travel toward the press bed at a high rate of speed, then to separate to cause one of said volumes of liquid to be directed to said ram motor to do the pressing work, and then to re-merge and be re-directed to the ram motor to cause it to return the ram to its starting position at a high rate of speed.

Another object of the invention is to provide improved apparatus as set forth in the foregoing object and wherein hydraulic fluid displaced by the ram motor when the

2

latter is operating to move the ram at a high speed is added to the hydraulic liquid being supplied to said motor to increase speed of operation of the latter.

Another object of the invention is to provide improved valve structure for the purposes set forth in the foregoing objects which includes a spool which is moved from one position to another by different pressures created at its opposite ends by hydraulic liquid flowing through it and in which there is improved means for causing said different pressures.

Still another object of the invention is to provide improved orifice means for causing liquid flowing therethrough to create different pressures at opposite sides thereof which includes a pair of orifice means of different sizes and a valve means between them responsive to the pressure of fluid applied to the first orifice means to by-pass the second and smaller orifice means.

Further objects and advantages of the present invention will be apparent from the following description, reference being had to the accompanying drawings wherein a preferred form of embodiment of the invention is clearly shown.

In the accompanying drawings:

Fig. 1 is a side view of a hydraulic press including the features of the invention, the view showing the press frame in section, which section is taken on line 1—1 of Fig. 2, looking in the direction of the arrows;

Fig. 2 is a front view of the hydraulic press seen in Fig. 1 with the frame broken away to the plane indicated by the line 2—2 in Fig. 1;

Fig. 3 is a view in plan of the hydraulic press seen in Figs. 1 and 2; and

Figs. 4, 5 and 6 are diagrammatic views showing the structure of the hydraulic apparatus or power unit of the press seen in Figs. 1, 2 and 3 and illustrating its novel features and operation.

This application is a division of my copending application Serial No. 559,438, filed January 16, 1956, now Patent No. 2,927,558 dated March 8, 1960 for "Hydraulic Press and Control Means."

The hydraulic press shown in Figs. 1 through 3 of the drawings has a frame 20 of the open gap or C type which may be formed as by casting or by fabrication from plates which are cut and shaped and then welded into an integral unit. The frame 20 is hollow for the purpose of receiving and housing the hydraulic apparatus or power unit 21 and the electric motor 22 of the press and it includes a bed 23, an upright open backed portion 24 and a head portion 25 which extends from the top of the upright back portion 24 forwardly over the bed 23. The bottom part of the upright portion 24 forms a tank or reservoir 26 for storing hydraulic liquid, preferably oil, which is employed in the hydraulic apparatus or power unit 21 of the press.

As clearly shown in Figs. 1 through 3 of the drawings, the hydraulic apparatus or power unit 21 of the press is a compact assembly which is contained substantially wholly within the head portion 25 of the frame 21 and above the bed 23. The power unit 21 includes a body, casing or housing formed of two separate housings or casings, namely, a body, casing or housing 27 for a pump 28 and a body, casing or housing 29 for control mechanism and a hydraulically operated ram motor.

The power unit 21 will be described in detail herein after, but it is pointed out here that it includes a piston shaft which forms the ram 32 of the press and that it is

so mounted in the head portion 25 of frame 20 that the ram 32 thereof projects downwardly through the bottom wall of the head portion 25 and extends toward the center of the bed 23. Hydraulic liquid is supplied to and exhausted from the power unit 21 by a supply conduit 33 and a drain conduit 34 which extend into the tank or reservoir 26. The electric motor 22 is mounted in the upper portion of the upright frame portion 24 above the tank or reservoir 26 by brackets 35 and it drives the pump 28 through sheaves and a belt 36.

The hydraulic apparatus or power unit 21 of the press is shown diagrammatically in Figs. 4, 5 and 6. This apparatus includes the hydraulically operated press ram 32 which, as shown, is formed by the piston rod of the reciprocating hydraulic ram operating motor 31. Motor 31 includes a cylinder 37 and a piston 38. The hydraulic apparatus or power unit 21 also includes the control mechanism indicated generally by the numeral 30, the pump 28 which is driven by the electric motor 22 and the reservoir or tank 26.

The control mechanism 30 and the ram motor 31 are contained within the body, casing or housing 29 which is formed by a body or casting 38' and a cap 39 secured together in fluid tight relation by bolts or screws, not shown, and a gasket 40. The body 38' includes a central bore in which a sleeve 41 is pressed axially and clamped against a shoulder 42 in body 38' by a shoulder 43 surrounding the mouth of a stepped bore 44 in cap 39. Sleeve 41 includes a plurality of external channels or grooves 45, 46, 47, 48 and 49 separated by lands which engage the walls of the bore in body 38' whereby the channels 45 through 49 form passages through which hydraulic fluid may pass circumferentially around the sleeve 41. Each of the channels or grooves 45 through 49 is connected to the interior of the sleeve 41 through ports and these ports are controlled by lands and grooves on a hollow valve piston or spool 50 which is slidably axially within the sleeve 41.

Spool 50 includes an internal wall or partition which forms an orifice 51 and a valve seat against which a poppet 52 having a central orifice 53 seats. Poppet 52 is preferably, but not necessarily, made of nylon and it is urged by a spring 54 contained within the lower portion of the spool 50 to seat against the partition as above described. This spring 54 acts through the poppet 52 to urge the spool upwardly to the position shown in Fig. 4 of the drawings where the upper end of spool 50 abuts a shoulder on an unloading piston 55 which is slidably positioned in the upper end of the bore in sleeve 41.

The unloading piston 55 includes an extension 56 which extends into the upper end of the spool 50 and which is slotted at 57 to receive a pin 58 which extends therethrough and is secured to the spool 50. The function of the lost motion connection provided by the pin 58 and slot 57 will be made apparent hereinafter. Unloading piston 55 is also provided with an annular lip 59 adapted to abut the upper end of sleeve 41 to limit its inward movement into the sleeve 41 and it is urged downwardly to the position shown in Fig. 4 of the drawings by a compression spring 60 contained within the bore 44 of cap 39. The body 38' also houses a valve 61 which is normally open and is urged to a closed position by a solenoid, for example, indicated diagrammatically at 62.

In Fig. 4 of the drawings, the parts of the above described structure are shown in the positions which they occupy when the ram 32 is held in its "up" position. Before describing the operation of the apparatus, it should be stated that the pump 28 has two outlet or output ports which are connected respectively to inlets, conduits or lines 63 and 64 formed in the body 38 and that the volume of fluid delivered to the lines 63 and 64 are preferably, but not necessarily, different. In one embodiment of the invention, the output volume of liquid to line 63 is approximately one gallon per minute and the output vol-

ume of liquid to line 64 is approximately two gallons per minute. While pump 28 is herein shown and described as one unit having dual outlets, it is to be understood that two separate pumps may be employed if desired.

As shown in Fig. 4, hydraulic liquid flows from the reservoir or tank 26 through the conduit 33 to the pump 28 where it is divided as aforesaid and flows to lines 63 and 64 under pressure. Liquid from the low volume output port of pump 28 flows through line 63 to groove 45 in sleeve 41 and from this groove 45 it passes to the interior of the upper end of spool 50 and also to a conduit, line or passage 65, the valve 61, a conduit, line or passage 66 to groove 46 in sleeve 41, and through an annular groove 67 in spool 50 to groove 47 in sleeve 41. From groove 47 liquid flows through a conduit, line or pipe 68 to conduit, line or pipe 64 where it combines or merges with liquid discharged from the high volume output port of pump 28. Because pressure of the liquid will pass through the partition in valve spool 50, the spring 54 will maintain the valve spool 50 in the position shown in Fig. 4 of the drawings until the valve 61 is closed.

The liquid flowing from conduit 68, as previously mentioned, merges or mixes with the liquid flowing in conduit 64 and thus, at this time, the total or combined output volume of pump 28 is supplied through conduit 64 to the bottom of cylinder 37 to elevate the piston 38 and ram 32. When piston 38 is in its uppermost position, liquid entering the cylinder 37 from conduit 64 is discharged from the cylinder 37 through a conduit 69 which leads to groove 49 in sleeve 41. From groove 49, this liquid flows through a groove or channel 70 in spool 50 to channel or groove 48 in sleeve 41 and through drain or exhaust line 34 to reservoir or tank 26.

When it is desired to start the ram 32 to descend toward the press bed, the solenoid 62 of valve 61 is energized to cause valve 61 to close. When valve 61 closes, hydraulic liquid flowing in conduit 63 passes through groove 45 in sleeve 41 and from this groove to the interior of the upper end of valve spool 50 and also to valve 61 where its flow is blocked. The pressure of the fluid flowing from groove 45 to the interior of valve spool 50, however, will increase and force the fluid to flow through the orifice 51 in spool 50 and the orifice 53 in poppet 52 to the interior of the lower portion of spool 50. From the bottom of spool 50, liquid flows through by-pass conduit 71 through a check valve 76, conduit 66, groove 46, groove 67 in spool 50 to groove 47, and conduit 68 to conduit 64. The liquid flowing through orifices 51 and 53, of course, creates a pressure differential between the upper and lower ends of the valve spool 50 and the spool 50 is thereby caused to compress the spring 54 and move spool 50 downwardly to the position shown in Fig. 5 of the drawings. This action or movement of the spool 50 occurs very quickly when liquid flows through the orifices 51 and 53. After spool 50 moves downwardly, liquid flows from the bottom of spool 50 through openings or ports in the bottom of sleeve 41 to channel 70 in spool 50, groove 49 in sleeve 41 and conduit 69 to the top of cylinder 37 and piston 38.

When the valve spool 50 is moved downwardly, as above-described, to the position shown in Fig. 5, hydraulic liquid flowing from the high volume output port of pump 28 in conduit 64 travels through conduit 68 to groove 47 in sleeve 41 and from it through a check valve 72 and conduit 71 to the bottom of spool 50 where it combines or merges with the output from the low volume output port of pump 28 and flows through the passages described to the top of the cylinder 37 and piston 38. This liquid, of course, will move the piston 38 downwardly and the liquid below the piston 38 will be expelled through conduit 64 and be combined or merged with the fluid entering the conduit 64 from the high volume output port of pump 28. It will thus be seen

that the piston 38, which is an unbalanced piston, will be moved downwardly rapidly since the combined output volumes of both of the output ports of pump 28 and the output from the bottom of cylinder 37 are merged and supplied to the top of the piston 38.

It should be noted that once the spool 50 has been moved to the position shown in Fig. 5 that valve 61 may be opened since the output line 66 thereof is closed by the isolation of groove 46 from the interior of sleeve 41 by a land on the spool 50. In other words, there are present two valves connected in series and either may function to block the flow of liquid from the groove 45 and the upper end of valve spool 50. It should also be noted that the maximum pressure in the top of cylinder 37 is controlled by an adjustable relief valve 73.

The ram 32 will travel freely toward the press bed 23 at a "fast traverse" speed until the ram 32 engages work on the bed, for example, after which, of course, very little liquid will be displaced from the bottom of cylinder 37. The resistance offered to the movement of the ram 32 upon engaging work on the bed 23 will cause the pressure in the cylinder 37 above the piston to increase and this increase in pressure will be reflected to the top of spool 50 to cause the unloading piston 55 to move upwardly to compress spring 60 and rest upon a shoulder or stop in the bore 44 in cap 39.

As the unloading piston 55 moves upwardly, the lost motion connection provided by the slot 57 in extension 56 and pin 58 lifts the valve spool 50 to the position shown in Fig. 6 of the drawings, and when the parts of the control unit 21 are in the position shown in said Fig. 6 only the pressure supplied from the low volume output port of pump 28 through conduit 63 is applied to the top of the piston 38. For this reason, substantially all of the energy of motor 22 is employed to drive pump 28 against the pressure of its low volume output port in conduit 63.

Upon the movement of valve spool 50 to the position shown in Fig. 6, all of the high volume output of pump 28 flowing in line 64 as well as the chamber formed in the bottom of cylinder 37 below piston 38 is connected to tank 26 through the conduit 68, groove 47 in sleeve 41 and 41, a groove 74 in spool 50, groove 48 in sleeve 41 and drain port or conduit 34. At this time all of the low volume pump output flowing in conduit 63 is directed to the top of piston 38 and the entire top area of said piston is effective to do work because the smaller bottom area thereof is exposed to tank pressure as described above.

The maximum pressure that can build up in the cylinder 37 above piston 38 is controlled by the adjustable relief valve 73. When the ram 32 encounters a resistance in its movement toward the press bed 23 sufficient to cause valve 73 to open, the ram movement stops and the full flow of liquid from the low volume output port of pump 28 flowing in conduit 63 is directed through groove 45, line 65, valve 61, conduit 66, groove 46 to relief valve 73 and drain conduit 34 to tank 26. Because the motion of ram 32 has stopped, there will be substantially no flow of liquid through the orifices 51 and 53 and the spool 50 will be returned to the position shown in Fig. 4 of the drawings by the spring 54 whereby the ram 32 will be moved at a rapid rate of speed to its "up" position and the parts of the control unit 21 will be placed in readiness for the next cycle of operation of the press ram.

As previously set forth, the pump 28 delivers two output volumes and as stated, in one embodiment of the invention these output volumes are one and two gallons per minute. It has been found in practice, however, that as the output pressures of the pump increase the output volumes will decrease due to inefficiencies of the pump and leakages of fluid therein. Because of this fact, the poppet 52 including the orifice 53 is provided in spool 50. The orifice 53 in poppet 52 is of less diameter than

the orifice 51 in the partition in spool 50 and when the output pressure of the low volume output port of pump 28 is low and valve 61 is first closed, as described in connection with Fig. 1, the volume and pressure of liquid flowing to the top of spool 50 is such that it will pass through the orifice 51 and lift the poppet 52 off of its seat while moving the spool 50 downwardly without lifting the unloading spool 55. As the volume of liquid pumped to the top of spool 50 decreases due to increased pressure, the poppet 52 which is being urged to its closed position causes orifice 53 to become effective to restrict the flow of liquid and thereby provide the necessary pressure differential between the opposite ends of spool 50 to hold it in the position seen in Fig. 5. It will thus be seen that the poppet 52 and orifices 51 and 53 cooperate to provide an assembly including variable orifice means which is responsive to provide the necessary pressure differential at opposite ends of the spool 50 even though both the pressure and volume of liquid supplied to the top of spool 50 may vary.

It is pointed out that if the valve 61 is held in its closed position that the automatic reversal feature of the apparatus which occurs when valve 73 opens will be prevented from becoming operative until the valve 61 is permitted to open. Thus, a press operator by keeping the solenoid 62 energized may cause the ram 20 to "dwell" upon the work.

From the foregoing description, it will be seen that the invention provides a control unit 21 which may be employed with facility, for example, in a hydraulic press to cause the press to "idle" with its ram held in a retracted position and that to initiate a cycle of operation of the ram it is necessary only to close the valve 61 momentarily, or until the valve spool 50 shifts from the position seen in Fig. 4 to the position seen in Fig. 5 of the drawings and that thereafter the cycle of operation, namely a rapid approach of the ram to the work, a build-up of ram pressure to the setting of valve 73, and a rapid return of the ram to its "up" or press "idling" position.

It will also be obvious that when the ram is travelling toward the work that both volumes of liquid pumped by the pump and liquid displaced from below the piston 38 are merged and supplied to the top of cylinder 37 to force the piston 38 downwardly at a high rate of speed and that when in its downward movement the ram 32 meets sufficient resistance to increase the hydraulic pressure above the piston 38 and spool 50 to lift the unloading piston 55 and spool 50, that only the smaller output volume of pump 28 flowing in conduit 63 is applied to the top of piston 38 and the higher output volume of pump 28 flowing in conduit 64 and the bottom of the motor cylinder 37 are connected to exhaust.

This condition will continue to exist until the hydraulic pressure above the piston 38 increases and opens valve 73 at which time the spring 54 will return spool 50 to the position seen in Fig. 4 of the drawings wherein both volumes of hydraulic liquid being pumped by pump 28 will be merged and supplied to the bottom of piston 38 to elevate or retract the ram 32 at a high rate of speed.

It will be apparent from the above that this invention provides an improved hydraulic apparatus for operating the ram of a press, for example, wherein the ram is operated by two separate volumes of hydraulic liquid derived from two sources and which volumes of liquid are first merged and directed to the ram motor to cause the ram to travel toward the press bed at a high rate of speed, then to separate to cause one of said volumes of liquid to be directed to said ram motor to do the pressing work, and then to re-merge and be re-directed to the ram motor to cause it to return the ram to its starting position at a high rate of speed.

While the form of embodiment of the present invention as herein disclosed constitutes a preferred form, it is to be understood that other forms might be adopted, all coming within the scope of the claims which follow.

I claim:

1. A valve for directing the flow of two separate volumes of hydraulic liquid from two sources including a body having a first and a second inlet means and a first and a second outlet means, means forming a bore in said body, means forming a plurality of ports spaced axially along said bore including ports connected with said inlet and outlet means and a drain port, spool means in said bore for selectively interconnecting said port means, said spool means when in one position in said bore interconnecting ports to direct said separate volumes of liquid to said first outlet means, means for causing an increase in the pressure of one of said volumes of liquid to shift said spool means to a different position in said bore thereby directing both of said volumes of liquid to the second of said outlet means, means responsive to the pressure of liquid at said second outlet means for causing said spool means to shift to another position in said bore for directing said one volume of liquid to said second outlet means and the other volume of liquid to said drain port, and means responsive to a further increase in pressure of said one volume of liquid to shift said spool means again to direct said volumes of liquid to said first outlet means.

2. A valve for directing the flow of two separate volumes of hydraulic liquid from two sources including a body having a first and a second inlet means and a first and a second outlet means, means forming a bore in said body, means forming a plurality of ports spaced axially along said bore including ports connected with said inlet and outlet means and a drain port, spool means in said bore for selectively interconnecting said port means, said spool means when in one position in said bore interconnecting ports to direct said separate volumes of liquid to said first outlet means, means for causing an increase in the pressure of one of said volumes of liquid to shift said spool means to a different position in said bore thereby directing both of said volumes of liquid to the second of said outlet means, and means responsive to the pressure of liquid at said second outlet means for causing said spool means to shift to another position in said bore for directing said one volume of liquid to said second outlet means and the other volume of liquid to said drain port.

3. Apparatus for directing the flow of two separate volumes of hydraulic liquid from two sources including a first and a second conduit means for conducting said two volumes of liquid, a first and a second outlet conduit means for receiving said liquid and a drain conduit, valve means for selectively interconnecting said conduits and operable in one position to direct said volumes to said first outlet conduit, means for causing an increase in pressure in one of said volumes of liquid for shifting said valve means thereby directing said volumes to said second outlet conduit, means responsive to an increase in the pressure of said one volume of liquid for causing said valve to direct said one volume of liquid to said second outlet conduit and the other of said volumes to said drain conduit, and means responsive to a further increase in pressure of said one volume of liquid to cause said valve again to direct said volumes of liquid to said first outlet conduit.

4. Apparatus for directing the flow of two separate volumes of hydraulic liquid from two sources including a first and a second conduit means for conducting said two volumes of liquid, a first and a second outlet conduit means for receiving said liquid and a drain conduit, valve means for selectively interconnecting said conduits and operable in one position to direct said volumes to said first outlet conduit, means for causing an increase in pressure in one of said volumes of liquid to shift said valve means thereby directing said volumes to said second outlet conduit, and another means responsive to a further increase in the pressure of said one volume of liquid for causing said valve to direct said one volume of liquid to said second outlet conduit and the other of said volumes to said drain conduit.

5. In a valve apparatus for directing the flow of two separate volumes of hydraulic liquid from two sources including a first and second inlet conduit means for said separate volumes of liquid, a first and second outlet conduit means for said liquid and a drain conduit, valve means including ports and a spool for selectively interconnecting said conduits and operable in a first position to direct said volumes from said inlet conduits to said first outlet conduit and operable in a second position to direct liquid from said inlet conduits to said second outlet conduit and operable in a third position to direct liquid from one of said inlet conduits to one of said outlet conduits and the other inlet conduit to said drain conduit, means resiliently urging said spool to said first position, means in said spool forming an orifice through which liquid can flow from one end of said spool to the other, said orifice causing liquid passing therethrough to create different pressures at opposite ends of said spool for shifting said spool to said second position, liquid conducting means for conducting liquid from said one end of said spool to bypass said orifice, a first valve means for closing said liquid conducting means, a second valve means connected in series with said first valve means for closing said liquid conducting means, said second valve means being closed by shifting of said spool to said second position, pressure operated means responsive to an increase in pressure of the liquid at said one end of said spool for moving said spool to said third position, and a relief valve responsive to pressure at said one end of said spool and operable to relieve said pressure whereby said resilient means moves said spool to said first position.

6. In a valve apparatus for directing the flow of two separate volumes of hydraulic liquid from two sources including a first and second inlet conduit means for said separate volumes of liquid, a first and second outlet conduit means for said liquid and a drain conduit, valve means including ports and a spool for selectively interconnecting said conduits and operable in a first position to direct said volumes from said inlet conduits to said first outlet conduit and operable in a second position to direct liquid from said inlet conduits to said second outlet conduit and operable in a third position to direct liquid from one of said inlet conduits to one of said outlet conduits and the other inlet conduit to said drain conduit, means resiliently urging said spool to said first position, means in said spool forming an orifice through which liquid can flow from one end of said spool to the other, said orifice causing liquid passing therethrough to create different pressures at opposite ends of said spool for shifting said spool to said second position, fluid conducting means for conducting liquid from said one end of said spool to bypass said orifice, valve means for closing said fluid conducting means, pressure operated means responsive to an increase in pressure of the liquid at said one end of said spool for moving said spool to said third position, and a relief valve responsive to pressure at said one end of said spool and operable to relieve said pressure whereby said resilient means moves said spool to said first position.

7. In a valve apparatus for directing the flow of two separate volumes of hydraulic liquid from two sources including a first and second inlet conduit means for said separate volumes of liquid, a first and second outlet conduit means for said liquid and a drain conduit, valve means including ports and a spool for selectively interconnecting said conduits and operable in a first position to direct said volumes from said inlet conduits to said first outlet conduit and operable in a second position to direct liquid from said inlet conduits to said second outlet conduit and operable in a third position to direct liquid from one of said inlet conduits to one of said outlet conduits and the other inlet conduit to said drain conduit, means resiliently urging said spool to said first position, means in said spool forming an orifice through which

liquid can flow from one end of said spool to the other, said orifice causing liquid passing therethrough to create different pressures at opposite ends of said spool for shifting said spool to said second position, fluid conducting means for conducting liquid from said one end of said spool to by-pass said orifice, valve means for closing said fluid conducting means, and pressure operated means responsive to an increase in pressure of the liquid at said one end of said spool for moving said spool to said third position.
